WATER PISTOL WITH MECHANISM WHICH
DISCHARGES A SUCCESSION OF WATER
SHOTS

Wesley C. Casson, Old Greenwich, Conn.

Application July 29, 1950, Serial No. 176,659

14 Claims. (Cl. 222—79)

1

This invention relates to liquid discharge devices and more particularly to a toy which effects a plurality of successive shots or discharges of liquid from a single load thereof.

The instant invention provides a toy such as a water pistol which ejects a charge of water by a succession of individual shots until the charge is exhausted. In a preferred embodiment, a hammer is provided by means of which the mechanism is cocked, such cocking action being simultaneously effective in drawing up a new charge of water from a reservoir in the pistol body. A particular feature of one aspect of the invention is that all the foregoing parts may be so arranged as to effect an extremely accurate simulation of a conventional repeater gun, that is, a single action 6-shot gun with a revolving cylinder. In the water pistol described herein, the cylinder does not revolve, but the action of the gun otherwise simulates that of the well-known gun above mentioned.

A further most important feature of the invention is the provision of trigger mechanism whereby the entire charge in the cylinder may be ejected at one shot. This is accomplished by disabling the action of the hammer in cocking the mechanism for a multiple discharge while permitting the hammer to swing back of its own accord after having been drawn in cocking position. Among other advantages, such mechanism enables the operator to perform a so-called "fanning" action. This action is spectacularly employed by cowboys or the like and is highly regarded by children as their imitators. One fans a gun by striking the palm of the hand against the hammer permitting it to return by itself instead of by actuation of the trigger. When the water pistol of the instant invention is fanned, it will discharge an entire cylinder load of liquid in one stream so as to produce a comparative drenching of the target. Thus, two optional and alternative methods of operation are provided. The first, a multiple discharge in a series of shots, and the second, a single stream of fluid comprising all the shots in the cylinder at one time. Preparation or cocking of the hammer for either type of operation draws up a supply of water and the action may be continued until the reservoir or chamber is exhausted. In a working model, the reservoir was formed in the handle or butt of the gun and contained about 50 charges, each of which could be ejected as a single charge, or in six individual and successive shots. Thus, about 300 individual

2

shots could be secured, or 50 full streams, or combinations of the two, as desired.

The above is a general description of the operation and form of the water pistol, but the invention will be further understood from the following description and drawings in which:

Fig. 1 is a central longitudinal section of the water pistol at the completion of the cylinder discharge and before cocking to refill the cylinder and repeat the discharge thereof.

Fig. 2 is a view similar to Fig. 1 and illustrating the cocking of the trigger mechanism.

Fig. 3 is a cross-sectional view taken along the lines 3—3 of Fig. 1.

Fig. 4 is an enlarged cross-sectional view taken along the lines 4—4 of Fig. 2.

Fig. 5 is an enlarged cross-sectional view taken along the lines 5—5 of Fig. 4.

Fig. 6 is a cross-sectional view taken along the lines 6—6 of Fig. 2.

Fig. 7 is a cross-sectional view taken along the lines 7—7 of Fig. 2.

Fig. 8 is a cross-sectional view taken along the lines 8—8 of Fig. 2.

Fig. 9 is a cross-sectional view taken along the lines 9—9 of Fig. 2.

Fig. 10 is a cross-sectional view taken along the lines 10—10 of Fig. 2.

The frame or casing of the water pistol is formed of two substantially similar halves, each of which may be molded or otherwise formed of suitable material, whether of plastic or metal, or the like. Thus, the half 15 may be produced of plastic in a suitable molding machine, and it, together with the half 16, houses most of the operating mechanism. Minor differences of form exist in the respective halves as will be discerned from the drawings herein, but in general, the halves are substantially identical. The handle or butt 17, which is formed when both halves are assembled, provides a reservoir 18 for water or other desired liquid 19. A wall 20 defines the upper end of the reservoir or chamber 18. A tube 21 extends from the lowermost portion of chamber 18 to a valve arrangement for charging the cylinder as will hereinafter be made clear. A plug 22 fits into an opening in the chamber 18 which permits refilling of the chamber with water. Plug 22 may be formed of rubber, soft plastic, or like material and is provided with a stem 23 and enlarged end 24 to permit refilling without complete removal of the plug and accordingly guarding against loss or displacement thereof.

Body half 16 is provided with a simulated ejec-

tor body 30 which may be cemented or otherwise secured in position. Body 30 is U-shaped in cross-section and houses intake tube 31 and intake valve body 32. Valve body 32 is formed with a bore 33 enclosing valve spring 34 and ball check valve 35.

Valve body 32 is integral with cylinder body 40 which is secured within the forepart of the gun barrel 41. The bottom of barrel 41 is formed with a slot 36 through which the valve body 32 protrudes so that it may be housed in the simulated ejector body 30. When the cylinder body is formed of a plastic substance, it may be cemented to the inner wall of barrel 41. An annular boss 42 serves as a stop or limit for the inner, open end of cylinder body 40. The outer or front end of cylinder body 40 forms the charge chamber 43 which communicates with bore 33 through a port 44. Thus, as water is drawn up through tube 31 and through the intake valve, as will be hereinafter described, it will fill the chamber 43 to be thereafter discharged therefrom.

An outlet valve tube 50 is integrally formed with cylinder body 40. Tube 50 is formed with a central bore 51 enclosing valve spring 52 and ball check valve 53. The function of valve spring 52, like that of other valve spring 34, is to urge the respective ball valves into their seats and into valve closing position. End piece 55 is fitted over the valve tube 50 and it also forms an enclosing wall 56 for the front or inner end of valve body 32. A metallic nozzle 57, which may be of brass or similar material, is screw-threaded into the forepart of end piece 55, such metallic nozzle being useful in preventing and excluding any obstruction in the water discharge path.

Cylinder body 40 houses the piston or plunger which may be formed of metal disks or washers 60 and 61 enclosing a felt disk 62. These disks are assembled over piston rod 63 and are pressed into position by piston spring 64 which also serves as the piston actuating spring.

The operating mechanism includes a fixed frame member 70 which supports the trigger elements. Frame 70 is of metal and includes an integral channel section 71 which extends into the barrel 41 and embraces piston rod 63. A cup 72 is assembled, cupped side forward, around the channel section 71, being supported against rearward movement by intermediate edges 73 of frame 70. Cup 72 both supports the frame 70 where it enters the barrel 41 and further serves as a rear seat for the piston spring 64.

Referring to Fig. 3, it will be observed that the body halves 15 and 16 are respectively formed with integral bosses 75 and 76 which jointly support fixed pin 77. The rear extremity of frame 70 is connected to pin 77 so that the frame is immovable relative to the pistol body. Frame 70 movably supports the trigger piece 80 by integral, inwardly bent lugs 81 and 82 of the frame 70 which are movably held in slots of the trigger piece. Thus, trigger piece 80 is provided with an arcuate slot 83 wherein lug 82 rides, and it is further provided with a trapezoidal shaped slot 84 in which lug 81 rides. As a result of such suspension of trigger piece 80, it is afforded a pivotal action wherein slot 83 dictates the initial pivotal movement of the trigger piece preliminary to an individual shot discharge while slot 84 controls the subsequent substantially downward movement of the trigger piece in completing the shot. A coil spring 85 normally maintains trigger piece 80 in a forward position where the lug 81 is adjacent the bottom edge of slot 84 while

the lug 82 is at the top of arcuate slot 83. This is shown in Fig. 1.

A pawl 86 is formed integrally with trigger piece 80. Pawl 86 actuates the teeth 87 of rack bar or arm 88 as will hereinafter be explained. The normal function of spring 85 is to draw the pawl 86 out of contact with teeth 87, while contact and actuation of the teeth is effected against the operation of spring 85 when the operator's finger is pressed against the trigger piece.

Rack bar or arm 88 is formed with a yoked end 89 which embraces pin 77 so that the rack bar is guided in a straight line movement. The front end of rack bar 88 is turned up to form lug 90 which penetrates through and rides in elongated slot 91 formed in the frame 70. Thus, rack bar 88 is supported at one end through the yoke 89 and pin 77, and at the other end by the lug 90 which rides in slot 91. Coil spring 85 is hooked into an opening 93 in lug 90 so that it urges rack bar 88 both rearwardly and downwardly. Formed on rack bar 88 is a dog or detent 92 which engages the ratchet teeth of the hammer body as will hereinafter be explained.

25 The hammer 95 comprises a thumb piece 96 which assumes conventional form and may be fabricated of plastic or like material. It embraces the metal ratchet 97 so that they jointly comprise a unitary hammer body. Ratchet 97 is formed with ratchet teeth 98 which are arcuately disposed and which are engaged by the dog or detent 92 in arresting return of the hammer after cocking thereof and after each individual actuation of the trigger.

35 Piston rod 63, after emerging through cup 72, is bent downwardly and flattened at its rearward end 100 where it is pivoted on eccentric pin 101 disposed on ratchet 97. The ratchet 97 of the hammer 95 is pivotally mounted on pin 77. It will be recognized therefore that the eccentric disposition of pin 101 causes piston rod 63 to be retracted as the hammer is retracted. Such retraction of piston rod 63 compresses piston spring 64 against cup 72 so as to prepare the piston for subsequent actuation and water discharge from the cylinder. It will be noted that as hammer 95 is retracted to its full rearward position, as illustrated in Fig. 2, the dog 92 is brought into engagement with the last of the ratchet teeth 98. This occurs because rack bar 88 is normally driven rearwardly by spring 85 so that the dog 92 will be maintained in engagement with ratchet teeth 98 immediately after the ratchet 97 comes to rest.

55 The operation of the water pistol may now be summarized. Starting from the uncocked position, illustrated in Fig. 1, the hammer is retracted by the user so as to cause the ratchet teeth 98 to move upwardly and then be engaged in cocked position by the dog 92 which has been impelled rearwardly through the action of spring 85. The cocked position is illustrated in Fig. 2 where lug 90 is in rearward position in slot 91 and the slot of yoke 89 is at its extreme rearward position so that its base embraces pin 77. At this time, it will be noted that pawl 86 is directly below the first tooth of rack bar teeth 87. During rearward actuation or cocking of the hammer, the piston was retracted so as to create a suction in the cylinder. This unseated ball check valve 35 against the action of spring 34 and drew up a charge of water from reservoir 18 through intake tube 31 and through slot 44 into the cylinder chamber 43. Ball check valve 53 was, of course, seated in place by action of the spring

52 so that the water could not be forced through the discharge outlet. As a result, the charge chamber 43 becomes filled with water as the piston retracts. The pistol is now ready for discharge of the water.

Assuming now that the operator prefers to discharge the water in chamber 43 in individual shots, he will press his index finger against trigger piece 89. This actuates the arcuate slot 83 so that the lug 82 reaches the bottom end thereof as to effect a pivotal movement of the trigger. The result of such action is to bring the pawl 86 into engagement with the first tooth of rack teeth 87. Thus, the arcuate slot 83 serves to effect engagement between the pawl and the rack bar teeth against the action of spring 85 which normally draws it out of such engagement. When the trigger has reached the limit of its pivotal movement through the restraining action of slot 83, it thereafter can continue in a substantially downward direction through the action of lug 84 in slot 94. This causes the pawl 86 to advance the rack bar 88 and urges dog 92 out of engagement with teeth 98. Dog 92 then comes to rest on the succeeding ratchet tooth. Meanwhile, the piston has been actuated forwardly one step. The pressure upon the water in charge chamber 43 then unseats ball check valve 53 against the action of spring 52 and ejects one-sixth of the water charge through nozzle 51, thus concluding an individual shot. The operator having released the trigger 80, spring 85 draws the pawl 86 out of engagement with the rack bar teeth, and the pistol may again be fired. This action may be continued six times or until the dog 92 has reached the last tooth of ratchet teeth 98 and the piston is in extreme forward position having ejected all the water in the charge chamber. The foregoing action may be repeated in quick succession so that the six shots are speedily ejected each time the trigger is pulled back and released.

Assume now that the operator desires to eject the entire charge in a single stream by the fanning action hereinabove described. He first pulls the trigger 80 back, in the position illustrated in Fig. 1, so that the pawl 86 engages the rear end or last tooth of the rack bar 88 so as to prevent the rack bar from moving rearwardly through the action of spring 85 in the manner described for a single shot action. As a result, rack bar teeth 87 may not be thereafter successively engaged by pawl 86. Then the hammer is retracted, charging the cylinder, with the rack bar 88 maintained forwardly so that dog 92 may not engage ratchet teeth 98. As a result, there is nothing to prevent immediate return of ratchet 97 as impelled by the piston spring 64 which was compressed by the rearward actuation of the hammer ratchet 97. This causes the piston to fly forwardly and discharge all of the water in chamber 43 in one stroke. The entire charge will be ejected through nozzle 51 so as to result in a heavy, drenching stream. This action will be most effectively performed by fanning the hammer where the trigger will be held in retracted position while the lower palm of the other hand may strike the hammer so as to actuate it rearwardly and permit its quick release to produce the single, entire discharge.

It will be recognized from the above that I have produced a water pistol which largely simulates the cocking and trigger action of a conventional gun while actually producing a water pistol having a discharge cylinder wherein the contents

may be discharged in successive, discrete shots or in a full stream at the option of the user. The functions of most of the elements of the trigger and cocking mechanism are generally multiple in order to minimize the number of elements and economize in the production and assembly of the water pistol. Whereas the invention has been described with reference to a water pistol, it will be evident that the principles and construction may be applied to analogous devices or toys such as a water discharging fire engine or the like.

What is claimed is:

1. A water pistol comprising a body, a water chamber formed in said body, a charge cylinder in said body and communicating with said chamber, a piston including a piston rod for applying pressure to a charge of water in said cylinder for discharging it therefrom, a spring normally urging said piston into forward or water discharging position, a hammer connected to said piston rod for retracting said piston against the action of said spring, said water pistol body being formed with a pistol barrel, said cylinder being disposed in said barrel, an outlet valve disposed forwardly of said cylinder within said barrel, an intake valve for charging said cylinder, a tube connecting said intake valve with said water chamber, a hammer body on said hammer, said hammer body being pivotally mounted within said water pistol body, said piston rod being eccentrically connected to said hammer body and producing a substantially linear movement of said piston when said hammer body is pivoted, and means including a trigger for advancing said piston in discrete, predetermined steps so as to discharge predetermined, discrete quantities of water from said charge cylinder.

2. A water pistol comprising a body, a charge cylinder in said body, a piston for applying pressure to a charge of water in said cylinder for discharging it therefrom, a spring normally urging said piston into forward or water discharging position, a hammer including an upstanding thumb-piece thereon, said hammer being pivoted relative to said body and being pivotally attached to said piston for retracting said piston against the action of said spring, a detent for maintaining said piston and hammer in retracted position and means for disabling the action of said detent whereby said piston is free to return to water discharging position after retraction thereof.

3. A water pistol according to claim 2 and including a trigger, said last named means being formed on said trigger.

4. A water pistol comprising a body, a water chamber formed in said body, a charge cylinder in said body and communicating with said chamber, a piston including a piston rod in said body for applying pressure to a charge of water in said cylinder for discharging it therefrom, a spring bearing against said piston for normally urging it into forward or water discharging position, a hammer body connected to said piston rod for retracting said piston against the action of said spring, a frame member in said body, an arm having rack teeth and having a detent, said arm being slidably supported against said frame member, ratchet teeth formed peripherally of said hammer and adapted to be engaged by said detent for maintaining said piston in retracted position, a trigger extending from said body and having a pawl for engaging said rack teeth and actuating said arm so as to release said detent from said ratchet teeth, and a second spring for urging said arm and said detent into engagement

with said ratchet teeth, said second spring being connected to said trigger for normally maintaining it out of engagement with said arm rack teeth.

5. A water pistol comprising a body including a barrel, a water chamber formed in said body, a charge cylinder in said barrel, a tubular conduit extending from said chamber, valve means connecting said charge cylinder with said tubular conduit, a piston including a piston rod in said body for applying pressure to a charge of water in said cylinder, outlet valve means for effecting discharge of said water from said cylinder, a coil spring in said barrel and around said piston rod and bearing against said piston for normally urging it into forward or water discharging position in said barrel, a hammer pivoted relative to said body, said piston rod being eccentrically connected to said hammer for retracting said piston against the action of said spring as said hammer is pivoted, ratchet teeth formed on said hammer, a detent for engaging said ratchet teeth so as to maintain said piston in retracted position, a frame within said body, a trigger pivotally connected to said frame, a pawl on said trigger for successively releasing said ratchet teeth from said detent at each reciprocation of said trigger, and a seat for said spring within said barrel and connected to said frame.

6. A water pistol comprising a body, a charge cylinder in said body, a piston in said body including a piston rod for applying pressure to a charge of water in said cylinder for discharging it therefrom, a first spring bearing against said piston for urging it into extreme forward or complete water discharging position in said cylinder, a movable hammer connected to said piston rod for cocking the piston in retracted position in said cylinder against the action of said spring, a ratchet having teeth formed on said hammer and movable therewith, an arm in said body including a detent for engaging said ratchet teeth to maintain said piston in retracted position, a second spring connected to said arm for urging said detent into engagement with successive ratchet teeth as said hammer is moved, a reciprocating trigger extending from said body, rack teeth on said arm and adapted to be engaged by said trigger at each reciprocation of said trigger for actuating said arm against the action of said second spring so as to move said detent out of contact with successive ratchet teeth as said trigger is reciprocated whereby said first spring is permitted to advance said piston together with said hammer and ratchet teeth for discharging the water in said cylinder in discrete steps, and whereby said second spring urges said detent into engagement with successive ratchet teeth.

7. A water pistol according to claim 6 and including a pawl on said trigger for engaging said rack teeth and actuating said arm as said trigger is reciprocated.

8. A water pistol according to claim 7 and wherein said second spring which is connected to said arm is also connected to said trigger at an opposite end of the spring for normally maintaining said pawl out of contact with said rack teeth.

9. A water pistol according to claim 8 and wherein said hammer is pivoted within and in respect to said body, said piston rod being eccentrically connected to said hammer whereby pivoting of said hammer retracts said piston rod and piston.

10. A water pistol comprising a body, a water chamber formed rearwardly of said body, a charge

cylinder forwardly of said body and communicating with said chamber, a piston in said body including a piston rod for applying pressure to a charge of water in said cylinder for discharging it therefrom, a spring bearing against said piston for normally urging it into forward or water discharging position, a hammer including an arcuate, pivoted hammer body connected to said piston rod for retracting said piston against the action of said spring, a frame member in said body, an arm having rack teeth and having a detent, said arm being slidably supported against said frame member, ratchet teeth formed peripherally of said hammer body so as to be arcuately arranged, said ratchet teeth being adapted to be engaged by said detent for maintaining said piston in retracted position, a trigger extending from said body and having a pawl for engaging said rack teeth and actuating said arm so as to release said detent from said ratchet teeth, and a second spring for urging said arm and said detent into engagement with said ratchet teeth.

11. A water pistol comprising a body including a pistol barrel, a charge cylinder in said barrel, a normally spring closed outlet valve disposed forwardly of said cylinder, a piston in said barrel for applying pressure to a charge of water in said cylinder when forwardly impelled for discharging it through said outlet valve, a rear water chamber formed in said body, means including an intake valve means forming an airtight path between, and disposed between, the forepart of said cylinder and said water chamber when said outlet valve is closed and the piston is retracted whereby retraction of said piston draws water through said intake valve and charges said cylinder, a piston spring bearing against said piston for normally urging it into forward or complete water discharging position, a hammer pivoted relative to said body and including an upstanding thumbpiece, said hammer being pivotally connected to said piston for retracting said piston against the action of said piston spring when the hammer is pivoted, a detent in said body for automatically maintaining said piston in retracted position by engaging said hammer and a trigger extending from the body and being adapted to prevent such engagement whereby said piston may freely return to forward or complete water discharging position after retraction thereof.

12. A water pistol comprising a body including a pistol barrel, a charge cylinder in said barrel, a normally spring closed outlet valve disposed forwardly of said cylinder, a piston in said barrel for applying pressure to a charge of water in said cylinder when forwardly impelled for discharging it through said outlet valve, a rear water chamber formed in said body, means including an intake valve forming an airtight path between, and disposed between, the forepart of said cylinder and said water chamber when said outlet valve is closed and the piston is retracted whereby retraction of said piston draws water through said intake valve and charges said cylinder, a piston spring bearing against said piston for normally urging it into forward or complete water discharging position, a hammer pivoted relative to said body and including an upstanding thumbpiece, said hammer being pivotally connected to said piston for retracting said piston against the action of said piston spring when the hammer is pivoted, a detent in said body for automatically maintaining said piston in retracted position by engaging said hammer and a trigger pivoted in respect to said body, said trigger being adapted

to prevent such engagement whereby said piston may freely return to forward or complete water discharging position after retraction thereof, ratchet teeth formed peripherally on said hammer, a fixed frame within said body, an arm slidably mounted adjacent and in respect to said frame, said detent being formed on said arm for engaging said ratchet teeth and maintaining said piston in retracted position, rack teeth formed on said arm, a pawl formed on said trigger so as to be actuated when the trigger is pivoted, said pawl being adapted to engage said rack teeth and slide said arm and detent out of engagement with said ratchet teeth when the trigger is pivoted to actuate said pawl, and spring means in said body for urging said detent into engagement with said ratchet teeth and for urging said pawl out of contact with said rack teeth.

13. A water pistol according to claim 12 and including a pair of lugs formed on said frame and disposed in openings on said trigger for pivotally suspending said trigger, one of said openings being arcuate and limiting initial pivoting action of said trigger until said pawl engages one of said

rack teeth and the other opening permitting final movement of said trigger for actuating said arm against the action of said spring means.

14. A water pistol according to claim 13 and including a channel section integral with said frame, said channel section extending into said barrel and supporting said piston rod within its channel, and supporting said piston urging spring around the outside of said channel section.
